United States Patent Office.

E. G. LAMSON, OF WINDSOR, VERMONT.

Letters Patent No. 89,264, dated April 20, 1869.

IMPROVED ROCK-CHANNELLING MACHINE.

The Schedule referred to in these Letters Patent and making part of the same.

To all whom it may concern:

Be it known that I, E. G. LAMSON, of Windsor, in the county of Windsor, and in the State of Vermont, have invented certain new and useful Improvements in Stone-Channelling and Grooving-Machines; and do hereby declare that the following is a full, clear, and exact description thereof, reference being had to the accompanying drawings, and to the letters of reference marked thereon, making a part of this specification.

The nature of my invention consists in so constructing a "stone-channelling and grooving-machine" that one engine, and one line of shafting, may be made to operate one or both of two sets of cutting-instruments, placed one on each side of the machine, and the subordinate devices thereto.

In order to enable others skilled in the art to which my invention appertains, to make and use the same, I will now proceed to describe its construction and operation, referring to the annexed drawings, in which—

Figure 1 is a side elevation, and

Figure 2, a front elevation of my machine.

Figure 3 is a side view of the connecting-bar between the drill-holders, and

Figure 4 is a longitudinal vertical section of the main or driving-shaft.

A represents a steam-boiler and fire-box, the rear end of which is provided with an axle, B, having at its ends the wheels C, while the forward end of the boiler rests on a truck, D, resting on wheels E E, placed on the shaft F.

At the front end of the truck D is a cast standard G, with a circular hole through which the front end of the boiler is inserted, the boiler thus resting on the four wheels C C and E E, which move on the track H.

To the casting G is attached the entire cutting-machinery, and I thus dispense with the expense of a frame running back, the boiler being used for or in place of a frame, which I consider a very important part of my invention.

On top of the boiler A is placed the engine J, the piston-rod of which is, by a pitman, I, connected with the crank, or driving-shaft L, at and above the front end of the boiler, said crank-shaft having four bearings in standards K K, extending upward from the casting G.

At each end of the crank-shaft L is a crank, or flange M, so as to attach wrist-pins, to carry cutters on each side of the machine, and said crank-shaft also serves to feed the machine along on the track, and to run a force-pump when the cutting-mechanism is standing still, as will be hereinafter fully set forth.

The main shaft L is made in three pieces, as follows: One centre-part a, and two end-pieces b b.

On the central part a, on each side of the crank where the pitman I is attached, is a large face-plate, e, made fast to the ends of said central part, and serving the purpose of balance-wheels, and as flanges, for

the purpose of holding a bolt, d, which clutches into balance-wheels e e, attached to the inner ends of the side-portions b b of the shaft.

To the outer ends of said side or end parts of the shaft, the cranks M M, with their wrist-pins, are attached, to operate one set of cutting-instruments on each side of the machine.

The ends of the central portion a have holes or recesses bored in them, forming bearings for the inner ends of the two outside or end parts b b, as seen in fig. 4. By this arrangement it will be readily understood that both the cutting-mechanisms, on both sides, may be kept in operation at the same time, or either one or the other can be stopped, or run at pleasure.

R represent the standard-guides secured in some suitable manner a sufficient distance from the edges of the casting G, and in the space thus left between the standard-guides and the casting, the mechanism which operates the cutting-instruments is placed.

This mechanism is constructed as follows:

To the outside cranks M M, or to pitmen N N, connected with the same, I attach a bow-spring, O, to which the clamp P, which holds and carries the cutters, is secured.

Instead of a bow-spring, I may use a spiral spring, rubber or air-spring, or cushion, or, in fact, any flexible or yielding instrument introduced between the crank and clamp, for the purpose of taking the jar from the other parts of the machine, and also in assisting to give a greater force to the blow upon the rock.

When the gang of cutters or drills is lifted, such an elastic or flexible mechanism takes off the sudden strain from the crank-shaft as it lifts the drill easily, or, in other words, it takes on the load gradually, and as the flexible or elastic bow-spring is accumulative in its action and yielding, so much so that when the cutters or drills, as is sometimes the case, get stuck in the channel or groove that they cannot be lifted, the yielding of the two arms of the bow-spring, or the two arms with a spring between the two, the machine may keep on running, and the crank or wrist-pin turn entirely around without breaking any part of the machine.

The bow-spring, or flexible instrument, further enables me to run the machine much faster, and the faster it is run the harder and greater the blow upon the rock, and it does twice as much execution as when a machine is run, and only gets the heft of the drills and clamp upon the rock.

Through the intervention of a bow-spring, or any accumulative and flexible instrument, I am enabled to throw the cutters with great force at a horizontal or at any desired angle, the effect of the spring resembling that of the bow and arrow.

The experiments up to the time of the introduction of the bow-spring between the driving or crank-shaft and the drill-holder, never succeeded in getting much power beyond the weight of gravitation. When turned

at an angle from a perpendicular, the power was lost, except the drill be driven by steam or compressed air, and in the cases where the drill has been attached to the piston-rod of the engine, the machinery will soon become out of order from the jarring.

The bow-spring O is attached to the links f f, and these links to the clamp, or drill-holder P, which slides freely on the standard-guides R R.

The drills S S are attached to the clamps by means of a self-tightening clamp, or a clamp made to hold any kind of a drill in the usual manner.

The lower, or foot-clamp P, to which the engine is connected, as above described, is connected with the upper or head clamp P', by means of the connecting-bar T.

The cutters S S are firmly secured in the lower clamp P, and their upper ends inserted in a channel or socket in the upper clamp P'.

If one or more of the cutters should become smaller than the other, small blocks may be inserted at the top of such cutters in said socket, thus rendering the points of the cutters even or otherwise.

The connecting-bar T is inserted through a groove in the lower clamp P, immediately outside of the cutters, and has a projection, g, above and below said clamp, as seen in fig. 3. The upper end of said bar passes through a groove in the upper clamp P', and is held above said clamp by a pin passed through the same. By this means it will be seen I can readily lower the drills when the channel is deepened.

Upon the driving-shaft L is an eccentric h, which operates directly by a rod, i, upon a lever, m, to which lever is a double-acting pawl, n, connected to give a forward and backward motion to the machine at pleasure.

To the other end of the shaft, on which the double-acting pawl is operated, is a worm, which plays into a spiral, or worm-gear V, on the shaft, or axle F, thus driving the machine, by friction of the wheels E E, on the track H.

The great advantages of the feed-arrangement are that the eccentric h, on the driving-shaft, may be set in such a manner, in connection with the wrist-pins or cranks, so as to feed the machine along on the track at the time when the cutters are coming up after a

blow has been struck, or while the cutters are on the way down, in other words, it can be timed at pleasure.

It also very frequently happens that the machine, in its operation, comes in contact with permanent obstacles, and it is stopped in its forward movement, but when the friction feed is used, the clutch or wheels may keep on turning, and the driving-machinery is allowed to be in motion, and not break, or otherwise damage the machinery, while on the other hand, if the machine were fed along on the track by a rack and pinion, or other positive feed, something would be sure to give way if there were sufficient power in the engine.

The feeding-mechanism is operated by a lever, X, so that it can be made to feed either backward or forward, or not at all, as may be desired.

The crank-shaft L is further, by some suitable means, connected with a force-pump Y, to supply the boiler with water.

Having thus fully described my invention,

What I claim as new, and desire to secure by Letters Patent, is—

1. A stone-grooving or channelling-machine, which is moved upon a track, provided with a series of reciprocating cutters upon each side of the propelling-mechanism when the cutters are operated by means of a crank-shaft, which is formed in sections, substantially as and for the purposes set forth.

2. In a stone-channelling or grooving-machine, which is moved upon a track, and provided with reciprocating cutters, which operate on each side of the track, a mechanism which enables the operation of the cutters by one engine on either side of the track, or on both sides of the track at one time, substantially as set forth.

3. The notched lever, or bar X, connected to a rock-shaft under the boiler, which is attached to the feed-mechanism, to cause the backward or forward operation of the machine, by the means substantially as set forth.

In testimony that I claim the foregoing, I have hereunto set my hand, this 5th day of April, 1869.

E. G. LAMSON.
